UNITED STATES PATENT OFFICE.

AUGUST J. R. MARJENHOFF, OF CHARLESTON, SOUTH CAROLINA.

RAIL CLEANING AND SCRAPING DEVICE.

No. 892,172.

Specification of Letters Patent.

Patented June 30, 1908.

Application filed December 11, 1907. Serial No. 406,050.

To all whom it may concern:

Be it known that I, AUGUST J. R. MARJENHOFF, a citizen of the United States, residing at Charleston, county of Charleston, and 5 State of South Carolina, have invented a certain new and useful Improvement in Rail Cleaning and Scraping Devices, of which the following is a specification.

My invention relates to a new and useful 10 improvement in rail cleaning and scraping device, and has for its object to provide an exceedingly simple and effective device of this character by means of which rails on which a car of any character runs may be 15 scraped and cleaned, the invention being exceedingly useful in winter time when snow and water are frozen upon the tracks and endanger the passage of the car over said rails.

20 My device may be easily and quickly actuated by the motorman or operator of the car to remove any foreign surfaces or ingredients from the rails, thereby preventing the wheels of the car from sliding and insuring 25 perfect electrical connection between the rails and wheels of said car.

With these ends in view, this invention consists in the details of construction and combination of elements hereinafter set forth 30 and then specifically designated by the claims.

In order that those skilled in the art to which this invention appertains may understand how to make and use the same, I will 35 describe its construction in detail, referring by letter to the accompanying drawing forming a part of this specification, in which—

Figure 1, is a side elevation of my improvement, showing the same upon one end of the 40 car. Fig. 2, is a front elevation thereof, and Fig. 3, is a sectional view of the actuating mechanism.

In carrying out my invention as here embodied, A represents the body of a car to 45 which is fastened the depending brackets B by means of the bolts C, to this said depending bracket is pivoted the rocking levers D and D' at the points E and E' and the said rocking levers are connected to the rod D' 50 by means of the short levers G and G', the said rod being connected to the scraper arms F and F'. To one end of the scraper arms are attached the scrapers H and H' of any 55 desired shape or form by means of the small bolts I, the said scrapers being made to slide along on the top of the rails at an angle to

prevent scrapers from catching in rail joints and for the purpose of throwing dirt and other matter clear of rails and they also have small extensions adapted to fit on the inside 60 of rail edge or in the grooves of the rails where such is necessary. The opposite end of the scraper arms are pivoted to the depending brackets J and J' which are fastened to the bottom of the car by means of the 65 bolts K.

One end of each of the rocking levers is attached to the rod L, which passes through the floor of the car and the tubular casing M and is fastened into the sliding head N against 70 which one end of the spring O rests, the opposite end resting upon the floor of the car. Through the said rod L is fastened a pin L' which extends through the L shaped slots M', cut in opposite sides of the casing M. The cap 75 P having an opening cut in the top thereof for the insertion of the detachable handle Q is threaded upon the casing M.

In practice when the scraper is being used the spring O presses the head N upward and 80 the rod L being fastened to the said head must also be forced upward, thus holding one end of the rocker arm up and the opposite end down, which presses the scraper upon the track through the medium of the small levers G and G' and the scraper arms F and F', thus all foreign substances which are on the 85 track will be thrown aside.

When it is desired that the scrapers be taken out of engagement with the tracks, the 90 detachable handle Q if pressed downward until the pins L' have passed the full length of the L shaped slot M' when the handle will be slightly turned thus placing the pins in the lower portion of the said slots M', thus 95 will one end of the rocking levers be moved downward and the opposite end upward until the scrapers are lifted from the track.

Having thus fully described my invention, what I claim as new and useful is— 100

1. In combination with a car, a depending bracket, a rocking lever, a scraper arm, a short lever connecting one end of the rocking lever to the scraper arm, a second depending bracket to which is attached one end of the 105 scraper arm, a scraper attached to the opposite end of the last named member, a casing, having an L shaped slot cut in opposite sides thereof, a cap having an opening cut therein threaded upon said casing, a sliding head, a 110 rod attached thereto passing through the floor of the car and attached to one end of the

rocking levers, a pin extending through opposite sides of sliding head and fastening same to rod, a spring placed inside of the casing one end of which bears against the 5 floor of the car the other end against the sliding head holding it in an upward position, and a detachable handle, as specified.

2. The herein described combination of a track cleaner and scraper, having a scraper 10 arm, one end of which is attached to a depending bracket, a scraper fastened to the lower end of the scraper arm, rocking levers one end of each of which is attached to the scraper

by means of short levers, a rod attached to the opposite end of the rocking levers, a casing, a sliding head placed therein to which is attached said rod, a spring also within the casing, as and for the purpose set forth. 15

In testimony whereof, I have hereunto affixed my signature in the presence of two 20 subscribing witnesses.

AUGUST J. R. MARJENHOFF.
